CLAIM

The ornamental design for a rotatable display element for changeable message sign, as shown and described.

DESCRIPTION

FIG. 1 is a perspective view of a rotatable display element for changeable message sign, showing my new design;

FIG. 2 is an end elevational view thereof;

FIG. 3 is a top plan view thereof;

FIG. 4 is a side elevational view thereof;

FIG. 5 is a bottom plan view thereof;

FIG. 6 is a perspective view of one side panel of the rotatable display element;

FIG. 7 is an end elevational view thereof;

FIG. 8 is a bottom plan view thereof;

FIG. 9 is a side elevational view thereof;

FIG. 10 is a top plan view thereof;

FIG. 11 is a perspective view of the interior core element of the rotatable display element;

FIG. 12 is an end elevational view thereof;

FIG. 13 is a top plan view thereof;

FIG. 14 is a side elevational view thereof;

FIG. 15 is a bottom plan view thereof;

FIG. 16 is a perspective view of the side panel carrier element;

FIG. 17 is a bottom plan view thereof;

FIG. 18 is an end elevational view thereof;

FIG. 19 is a side elevational view thereof;

FIG. 20 is a top plan view thereof.
